UNITED STATES PATENT OFFICE.

HUGH J. DOWNEY, OF MODESTO, CALIFORNIA.

METALLIC RAILROAD-TIE.

1,083,064.

Specification of Letters Patent.

Patented Dec. 30, 1913.

Application filed February 19, 1912. Serial No. 878,586.

To all whom it may concern:

Be it known that I, HUGH J. DOWNEY, a citizen of the United States, residing at Modesto, in the county of Stanislaus and 5 State of California, have invented a Metallic Railroad-Tie, of which the following is a specification.

This invention relates to railroad ties of the metallic type and the principal object of 10 the invention is to provide a tie with which the rail may be securely connected, and which will support the rail in such a manner that it will be secure but resilient.

Another object of the invention is to provide 15 an improved type of plate for connecting the rail with the tie.

With these and other objects in view this 20 invention consists of certain novel combinations, constructions, and arrangements of 20 parts as will be hereinafter fully described and claimed.

In the accompanying drawing:—Figure 1 is a perspective view of one end of the tie. Fig. 2 is a perspective view of the plate 25 which connects the rail with the tie. Fig. 3 is a view partially in section and partially in elevation showing the manner of connecting a rail with the tie. Fig. 4 is a fragmentary top plan view of the tie with a rail 30 connected therewith.

This invention comprises a metallic casing 10 which forms the body portion of the tie and which is provided at each end with a cut-out portion 11 having under-cut inner 35 end portions 12, thus providing overhanging lips 13. The plate 14 which is shown in Fig. 2 fits against the base of the rail 15, and is provided with cut-out tongues 16 which are struck from opposite end portions of the 40 plate and bent upwardly to engage opposite side portions of the rail base as shown in Fig. 3. This plate is placed diagonally against the base of the rail and then turned to cause the tongues to engage the base as 45 shown in Fig. 3, and the end portions of the plate are then slipped into the proper position with the side portions of the plate fitting beneath the lips 13. It should be noted that the opening 11 is of such depth that the 50 plate 13 may be readily passed through the opening when the block 17 is not in place. The supporting block 17 is then driven into the body portion of the tie beneath the plate and the rail will then be securely connected 55 with the tie. This block 17 fits tightly into

place and holds the plate securely beneath the lips 13 with the tongues 16 on each side of the tie and against the lips 13. When it is desired to release the rail from the tie the block can be removed from beneath the plate 60 and the plate then easily slipped out of the slot and removed from the rail. The rail will then be free from the tie and a new tie can be provided or any necessary repairs made. It will, therefore, be seen that no 65 spikes are required when connecting this rail with the tie.

It should be noted that the slots 12 are of such depth that the blocks 17 will support the weight even when a train is passing over 70 the rail, thereby assuring resiliency which would be destroyed if the plate was allowed to come in contact with the side walls of the body portion. It should also be noted that by having the tongues 16 outside of and 75 against the overhanging lips 13, it will insure greater stability and obviate any displacement of rail or plate.

Having thus described the invention what is claimed as new, is:—

1. A tie comprising a hollow body portion provided with a transversely extending slot having its inner end portion under-cut to provide overhanging lips, a supporting block positioned in said body portion beneath the 85 slot formed therein, a rail engaging plate extending through the slot beneath the overhanging lips and resting upon said supporting block, and tongues struck from the end portions of said plate and bent upwardly to 90 engage opposite side portions of a rail.

2. A tie comprising a hollow body portion provided with a transversely extending under-cut slot forming overhanging lips, the lips constituting abutments, a supporting 95 block in said body portion beneath the slot formed therein, a plate extending through the under-cut portion of the slot formed in said body portion and resting upon said block, and rail engaging tongues struck from 100 said plate and bent upwardly to extend through said slot to engage the base of a rail, said tongues fitting outside and against said lips whereby the lips will form abutments for preventing longitudinal movement 105 of said plate on the rail.

HUGH J. DOWNEY.
